UNITED STATES PATENT OFFICE.

CHARLES H. LANDENBERGER, OF PHILADELPHIA, PENNSYLVANIA.

DESIGN FOR WOVEN FABRIC.

No. 38,949.

Specification for Design.

Patented Dec. 10, 1907.

Application filed October 9, 1907. Serial No. 396,672. Term of patent 3½ years.

To all whom it may concern:

Be it known that I, CHARLES H. LANDENBERGER, a citizen of the United States, residing in Philadelphia, Pennsylvania, have invented a new, original, and ornamental Design for Woven Fabric, of which the following is a specification.

The figure in the accompanying drawing is a face view of a piece of woven fabric showing my new design.

I claim;
The ornamental design for woven fabric,
as shown.

CHARLES H. LANDENBERGER.
